UNITED STATES PATENT OFFICE.

OLIVER J. BERG, OF OAK PARK, ILLINOIS.

SEAL FOR SOLID FORMALDEHYDE PRODUCTS.

1,371,724.

Specification of Letters Patent. Patented Mar. 15, 1921.

No Drawing.

Application filed February 7, 1920. Serial No. 357,026.

To all whom it may concern:

Be it known that I, OLIVER J. BERG, a citizen of the United States, residing at Oak Park, Cook county, Illinois, have invented certain new and useful Improvements Relating to Seals for Solid Formaldehyde Products, of which the following is a specification.

It is common practice to fumigate for 10 infecting purposes with formaldehyde vapors, and among other methods of operation, to employ fumigators comprising a heating unit and a receptacle containing a formaldehyde product in solid form, the 15 application of the heat to the container volatilizing the formaldehyde.

A serious difficulty has existed in sealing the formaldehyde product against its 20 deterioration through the lapse of time, which deterioration consists chiefly in the further polymerization and hardening of the formaldehyde, and the concentration of the formaldehyde through the evaporation of moisture in the product, whereby the 25 product sometimes becomes quite hard, sometimes falls to powder, and sometimes is otherwise either destroyed or injured.

It is the prime object of the present invention to provide a seal or preserving layer, 30 coat or covering for the formaldehyde product which effectively avoids the impairment of the formaldehyde product through aging, and by simple, cheap and easily applied means.

An illustration of the solid formaldehyde product herein referred to is what is commonly known to the trade as paraformaldehyde containing, for instance, sixty-five per cent. of polymerized formaldehyde and 40 thirty-five per cent. of water. The proportions and composition vary, however, in different products and the present invention is not limited to a solid formaldehyde product of any particular kind. In practice this 45 product is poured into cans or other containers while in a liquid condition and allowed to harden. The desideratum is to provide a seal for the exposed top surface of the product in the container.

Heretofore it has been common practice 50 to pour a layer of liquid paraffin upon the top surface of the formaldehyde product for the purpose of securing the same against the deleterious changes indicated hereinabove. Such coating, however, as the sole

sealing means is not satisfactory. One reason for this is that it is almost impossible to obtain so perfect a coating on the top surface of the product with paraffin or the like as not to leave air holes, and secondly, owing to the contraction of the formaldehyde body the hardened layer of paraffin is broken loose at edge portions or fissures are created in it impairing its character as a seal. Although the air passages in the paraffin may be small they effectively expose the entire top surface of the formaldehyde product.

The seal of my present invention comprises two parts or features; the first being a substance having the property of preventing the deleterious changes in the formaldehyde product mentioned, and serving also as a partial seal against evaporation, and avoiding the exposure of any materially large surface of the product even should openings occur in the second sealing part or feature; and the second part or feature having the property of preventing objectionable loss of formaldehyde through its evaporation.

The first part or feature of my complete seal mentioned contains a relatively large amount of glycerin and a relatively small amount of ammonium stearate, and preferably also a relatively quite small amount of stearic acid, when in the preferred form of substance which I employ. In making this substance I take about twenty-three-and-one-half parts by weight of glycerin ($C_3H_8O_3$), about three-and-one-half parts by weight of stearic acid ($C_{18}H_{36}O_2$) and about one-and-one-half parts by weight of say an approximately twenty-seven per cent. solution of ammonia (NH_3) in water (H_2O). These three substances are mixed together by heating and stirring, and, owing to the chemical reactions which take place, the resultant mass consists of glycerin and ammonium stearate, ($C_{18}H_{35}O_2.NH_4$) and a relatively small amount of stearic acid. I prefer to have an excess of stearic acid but the seal would be effective without such excess or even with an excess of ammonia.

This mixture has the consistency of fairly thick paste when cool. It is applied by warming it and pouring it upon the formaldehyde product in the container and allowing it to harden.

The ammonium stearate is a form of

thickening agent which I prefer to use in this connection, but the invention is not limited to a base of that particular kind. So far as I know, glycerin is the most satisfactory available substance having the peculiar properties desired in a seal of this kind for such formaldehyde products. I have discovered that other polyhydric alcohols and some carbohydrates exhibit corresponding properties in various degrees, and therefore the invention is not strictly limited to glycerin, although I consider it the most advantageous substance for the purpose described.

The second part or feature of the seal complete may be a layer of paraffin or the like upon the layer of the glycerin-containing mixture hereinabove described. It may be any suitable waxy or other substance which has the property of preventing evaporation of the formaldehyde and water in the formaldehyde product. It is pointed out that the first layer mentioned, while preventing deterioration of the formaldehyde product through chemical or physical changes incident to aging, does not in itself avoid all loss of material through the evaporation of formaldehyde and water. So long as the glycerin-containing sealing element covers the surface of the formaldehyde product the product will remain in its proper condition for use, but through evaporation of both water and formaldehyde the bulk will in time become less.

The second feature of the seal is therefore provided to prevent this loss of material through evaporation.

It is pointed out, however, that this second sealing element adapted to prevent evaporation does not need to be a wax-like or gummy coating as hereinabove mentioned, but may consist of the cover of the can itself, as where the can is provided with a screw cap, friction cap, etc., well known in the art, or it may be a tight box around the container, or a wrapping of oiled or otherwise treated paper around the container. In view of these teachings of the desirability of preventing evaporation, various other means for the purpose will

readily suggest themselves to those skilled in the art.

The present invention or discovery is not limited to the specific substances mentioned hereinabove, nor to the particular use or application pointed out, and reference should be had to the appended claims to determine the scope of the improvements herein set forth.

I claim:

1. A formaldehyde product and a preserving layer therefor which includes available glycerin.
2. A formaldehyde product and a preserving layer therefor which includes glycerin and a thickening substance providing, when mixed together, a mass of paste-like consistency.
3. A solid formaldehyde product and a preserving layer therefor comprising a relatively large amount of glycerin and a relatively small amount of a salt of a fatty acid of high molecular weight.
4. A solid formaldehyde product and a preserving layer therefor comprising a relatively large amount of glycerin and a relatively small amount of ammonium stearate.
5. A solid formaldehyde product and a preserving layer therefor comprising a relatively large amount of glycerin, a relatively small amount of ammonium stearate, and a relatively quite small amount of stearic acid.
6. A formaldehyde product and a covering element therefor including a polyhydric alcohol having the property of substantially maintaining the product against material deterioration and against material loss through evaporation.
7. A solid formaldehyde product and a covering therefor which comprises glycerin and a thickening substance, and also means for maintaining the product against material evaporation.
8. A solid formaldehyde product and a covering therefor comprising a mixture of a relatively large amount of glycerin and a relatively small amount of ammonium stearate, and means for maintaining the product substantially against evaporation.

OLIVER J. BERG.
